UNITED STATES PATENT OFFICE.

ERASTUS E. WINKLEY, OF LYNN, MASSACHUSETTS, ASSIGNOR TO UNITED SHOE MACHINERY CORPORATION, OF PATERSON, NEW JERSEY, A CORPORATION OF NEW JERSEY.

SHOE-POUNDING MACHINE.

Application filed May 12, 1925. Serial No. 29,730.

This invention relates to shoe-pounding machines. In the manufacture of various types of shoes, it is desirable to produce what is known as a close shank by closing 5 the shank portion of the crease between the welt and the upper of a welt shoe or between the sole and the upper in the case of a shoe which does not have a welt, this crease being usually termed the "welt crease" regardless 10 of whether the shoe is provided with a welt. This operation is customarily effected by pounding or beating the margin of the sole toward the last. Since the present invention has been developed as the result 15 of efforts on my part to provide an improved pounding machine adapted to close the welt crease in the shank of a shoe, the invention is herein illustrated and described with special reference to this problem. It is recognized, however, that in various aspects 20 the invention is not limited to embodiment in machines designed for shoe bottom beating or pounding, but may be embodied to advantage in machines having operating tools designed and adapted for other purposes.

The pounding machines designed for beating the shank portions of shoe soles to produce the close shank effect above referred to have usually been provided with rotary tools 30 each having a plurality of beating projections. In the use of such machines, the shoe is held up to the action of the rotary beating tool by the operator's hands and he has to exert a good deal of strength in order to obtain 35 the desired pounding action upon the sole. Moreover, holding the shoe manually against the rapidly rotating beating tool causes violent vibration of the shoe. For the purpose 40 of reducing the fatigue resulting from the conditions just stated, it is an object of this invention to provide a machine adapted to pound or beat shoe soles, in the use of which an effective beating action may be obtained 45 while holding the shoe only relatively lightly up to the tool and which will cause only a minimum of vibration of the work.

To this end, the invention provides a novel machine organization comprising an operating tool arranged for limited endwise movement to which percussional impulses are imparted by a hammer. In the illustrated machine, a relatively light tool designed for beating the shank of a shoe sole to close the

welt crease is operated by a relatively massive hammer. Thus, when the tool is actuated by the hammer, it absorbs but little of the momentum of the hammer. Moreover, the illustrated hammer is spring-impelled in addition to being influenced by gravity when suddenly released by a drop cam. The sharp blows of the heavy hammer so produced are transmitted by the tool to the work with but slight diminution since the mass of the tool is relatively small and the inertia of the shoe last is sufficient to absorb the force of the blows largely or wholly, so that there is no objectionable displacement of the shoe. The tool not only delivers sharp, quick blows, but these blows are so timed as to permit the work to recover considerably if not fully from the displacing effect of each blow before the next blow is struck. Moreover, to limit the endwise movement of the tool under the influence of the hammer, the illustrated beating tool carries a stop adapted to engage the frame if, in any given instance, the force of the blow is not substantially absorbed by the inertia of the work.

As a further feature of the invention, novel means is provided for initiating the operation of the hammer in response to pressure of the work. To this end, in the illustrated machine, the hammer is normally held in retracted position by a latch, and means responsive to pressure of the work operates to trip the latch to permit the hammer to act. The construction is such that a slight lifting movement of the tool under pressure of the work is sufficient to render the hammer operative. In consequence, the beating tool tends to displace the work only a short distance, and this further lessens objectionable vibration. As a further advantage, it will be observed that the hammer is inoperative unless the work is presented to it. Advantageously too, a member of larger area than the beating tool may be introduced between it and the work. As illustrated, a steel plate having one end with its edge upturned is disposed beneath the tool member, the other end of the plate being adjustably secured to the machine. This plate effectively transmits the action of the tool to the work.

These and other features of the invention will appear more fully from the following

detailed description when read in connection with the accompanying drawing and will be pointed out in the appended claims.

In the drawing:

Fig. 1 is a perspective view of the head of a machine embodying this invention, the front cover plate being partly removed;

Fig. 2 is a vertical section of the machine head taken from front to rear; and

Fig. 3 is a sectional view of a shoe being treated by the operating instrumentalities of the machine.

In the drawing, the numeral 2 indicates the frame of the machine head which is secured to the top of a column 4 resting on the floor and of suitable height so that the operator may present a shoe in his hands to the operating instrumentalities of the machine. A shaft 6 is journaled in the frame 2 and provided at one end outside the casing with a pulley 8 to which power may be applied. On the shaft 6 within the casing is a drop cam 10 which acts on a roll 12 carried by a hammer member 14 which is pivoted between its ends on a shaft 16. The forward arm of the hammer member 14 is massive and forms a hammer head 18. The head 18 is raised by the action of the cam upon the roll 12 and when released is impelled downwardly by gravity and by a spring 20 engaging at one end a stud 22 on the hammer member 14 about midway between its pivot 16 and the head 18. A rod 24 having a flange 26 is introduced into the opposite end of the spring 20, the rod 24 having a recess in its upper end which is engaged by the rounded end of a screw 28, this construction permitting the required movement of the spring during the operation of the hammer member. Tension of the spring may be varied by adjusting the screw 28, the adjusted position of which may be maintained by a set-nut 30.

Beneath the head 18 of the hammer and arranged for vertical reciprocation is a tool member 40. For the sake of lightness the member 40 is made hollow, as shown in Fig. 1, and being thus of small inertia readily acquires the velocity of the hammer member 14 and transmits its momentum to the work. The upper end of the tool member 40 is provided with a collar 42 which prevents it from dropping out of its guideway in the head and provides a stop to arrest the tool in case the force of the blow is not entirely absorbed by the work.

On the rear face of the member 40 is a recess 44 which is engaged by one arm 46 of a three-armed lever pivoted at 48, the arm 46 extending through an opening in the guideway of the member 40 and entering the recess 44. Another arm 50 of the three-armed lever is offset from the axis 48 so that one side of the arm 50 is in line with the axis about which it turns. The arm 50 is ar-

ranged to engage, when the hammer member is in its raised position, beneath a stop-screw 52 carried by the hammer member. The arm 50 is normally urged toward the position shown to maintain the hammer in raised position by a spring 54 located between a third arm 56 and the machine frame. It will be evident that upward pressure upon the tool member 40 will cause the arm 50 to swing out from beneath the stop-screw 52 to release the hammer and that thereafter the cam 10 will be effective to raise and release the hammer member the blows of which will be delivered to the tool member 40 and transmitted thereby to work held beneath the tool member, such action continuing until the upward pressure on the tool member is released, whereupon the spring 54 will act to swing the arm 50 beneath the screw and arrest the hammer member in its elevated position when next raised.

It is to be understood, of course, that the work may be presented directly to the lower end of the tool member 40. However, since the area of the end of the tool member is rather small, it is desirable under some conditions of work to provide beneath the tool member a member of larger area by which the effect of the tool member is distributed and any possible marring or marking of the work avoided. As shown, a light plate 60 extends beneath the end of the tool member 40 and has its edges upturned to prevent marring the work. The plate 60 is upwardly bent, back of the tool member, and has its rear end adjustably secured by screws 61 to a block 62 pivoted at 64 to a screw 66 threaded through the frame and having its inner end arranged to provide anchorage for the spring 54. Back of the pivot 64 is an extension 68 of the block 62 to which is threaded an adjusting screw 70 provided with a set-nut 72.

In using the machine, the operator presents the work held in his hands, substantially as indicated in Fig. 3, to the operating instrumentalities 40, 60 of the machine and presses the shoe upward. This lifts the plate 60 and tool member 40, releases the latch 50 and allows percussional impulses of the hammer member 14, 18 to be delivered to the tool member 40 and transmitted thereby through the plate 60 to the work. The direct blows thus delivered to the shoe are effective in bending and shaping the margin of the sole to close the welt crease and cause it, by repeated hammerings, to remain in that position.

Since the blows are delivered directly downward in a predetermined direction, the operator can, by manipulating the shoe, control the action of the tool and obtain the desired close shank effect. This result is obtained with less effort because the force of the blow is absorbed by the inertia of the

last with comparatively little sustaining effort on the part of the operator, and since but little displacement of the shoe is possible because of the small distance the tool member is lifted to set the hammer member in operation, the vibration imparted to the work by rapidly repeated blows is not great.

In operating on shoes provided with a channel flap that has not been laid the plate 10 60 will be used as a guide by being pressed against the base of the channel flap as the shoe is moved along.

Having thus described my invention, what I claim as new and desire to secure by Letters Patent of the United States is:

1. In a shoe pounding machine, the combination of a pounding tool mounted for vertical reciprocation, a stop for said tool, and a power operated spring-impelled hammer 20 for imparting percussional impulses to the tool to force the tool toward the stop when raised by the work.

2. In a machine of the class described, the combination of a frame, a tool arranged for 25 vertical reciprocation in the frame, a stop on the tool engaging the frame to limit movement of the tool, the tool being movable by the work to space the stop from the frame, and a spring-impelled hammer arranged to be raised and suddenly released to 30 strike a sharp blow upon the tool, movement of the tool by the hammer being limited by said stop.

3. In a machine of the class described, the combination of a spring-impelled hammer, 35 means for raising and releasing the hammer, a reciprocating member unconnected to the hammer arranged in the path of the hammer, and a stop for limiting movement of the member by the hammer, said member being movable by the work away from the stop.

4. In a machine of the class described, the combination of a rigid frame, a tool of little 45 inertia arranged for reciprocation in the frame, a stop on the frame engaged by the tool to limit movement of the tool, the tool being positioned away from the stop during operation of the machine, a momentum member of large mass relatively to the tool, and a spring means for imparting a high velocity 50 to said member to cause it to strike a sharp blow upon the tool, movement of the tool by the momentum member being limited by said stop.

5. In a machine of the class described, the combination of a spring-impelled momentum member, a light reciprocating tool member 55 arranged in the path of the momentum member and unconnected thereto, and a stop for limiting movement of the tool member by the momentum member, the tool being moved away from the stop to receive the impulse of the momentum member.

6. In a shoe pounding machine, a rigid 65 frame, a light pounding tool member ar-

ranged for reciprocation in the frame, a spring-impelled momentum member arranged to be raised and released to strike a sudden blow upon the tool member, and means for limiting movement thus imparted to the tool member.

7. In a shoe pounding machine, the combination of a rigid frame, a pounding tool of little inertia arranged for reciprocation in the frame, a stop on the tool engaging the frame to limit movement of the tool, the tool being movable by the shoe to space the stop from the frame, a momentum member of large mass relatively to the tool, means for imparting a high velocity to said member to cause it to strike a sharp blow upon the tool, and means for preventing operation of the momentum member unless a shoe is presented to the tool.

8. In a machine of the class described, the combination of a spring-impelled momentum member, a light reciprocating tool member arranged in the path of the momentum member and unconnected thereto, and a stop for limiting movement of the tool member by the momentum member, said tool member being movable by the work toward the momentum member.

9. In a shoe pounding machine, a rigid frame, a light tool member arranged for reciprocation in the frame, a spring-impelled momentum member arranged to be raised and released to strike a sudden blow upon the tool member, and means for limiting movement thus imparted to the tool member, said tool member being displaceable toward the momentum member by the shoe.

10. A shoe pounding machine having, in combination, a tool mounted for vertical reciprocation, a power operated oscillating hammer for imparting percussional impulses to the tool, means for rendering the hammer inoperative, and means operated by movement of the tool for rendering the hammer operative.

11. A shoe pounding machine having, in combination, a power operated cam, a hammer arranged for operation by said cam, means for holding the hammer out of operative relation to the cam, a tool to receive percussional impulses from the hammer, and means operated by movement of the tool for rendering the hammer holding means inoperative.

12. In a shoe pounding machine, the combination of a reciprocating tool, oscillating means for imparting percussional impulses to the tool, and a plate fixed as to movement transversely of the path of the tool located between the tool and the work for distributing the effect of the tool.

13. In a shoe pounding machine, the combination of a hammer lever pivoted between its ends, a power operated cam acting on one end of the hammer lever, a latch for up-

holding the other end of the hammer lever when lifted by the cam, and means operated by the work for moving the latch to permit operation of the hammer.

5. 14. A shoe pounding machine having, in combination, a hammer lever pivoted between its ends, a power operated cam acting on one end of the hammer lever, a latch for upholding the other end of the hammer lever

when lifted by the cam, a tool of small inertia mounted for reciprocating movement in the path of the hammer lever, and connections for releasing the latch upon movement of the tool by the work. 10

In testimony whereof I have signed my name to this specification. 15
